CLAIM

The ornamental design for a camera case, as shown.

DESCRIPTION

FIG. 1 is a front elevational view of a camera case showing our new design;

FIG. 2 is a rear elevational view thereof;

FIG. 3 is a right side elevational view thereof;

FIG. 4 is a top plan view thereof;

FIG. 5 is a bottom plan view thereof;

FIG. 6 is a front perspective view thereof;

FIG. 7 is a front elevational view with the case in extended position for receipt of a camera and with the upper clasp member in the closed position;

FIG. 8 is a right side elevational view thereof;

FIG. 9 is a top plan view thereof; and

FIG. 10 is a bottom plan view thereof.
